UNITED STATES PATENT OFFICE.

JOSEPH L. HILLER, OF MATTAPoisETT, MASSACHUSETTS.

CRUSHING OR PULVERIZING MACHINE.

977,799.

Specification of Letters Patent. Patented Dec. 6, 1910.

Application filed December 9, 1909. Serial No. 532,262.

To all whom it may concern:

Be it known that I, JOSEPH L. HILLER, a citizen of the United States, residing at Mattapoisett, in the county of Plymouth and State of Massachusetts, have invented new and useful Improvements in Crushing or Pulverizing Machines, of which the following is a specification.

This invention relates to improvements in crushing or pulverizing machines of the revolving hammer type, and has for its object to provide a novel means and arrangement whereby a relatively hard or less friable material may be separated from the softer or more friable material and separately discharged from the machine.

In run-of-nine coal slate and sulfur balls, and often metallic articles, such as bolts, spikes, etc., accompany the coal. The presence of such impurities and articles in the crushing-machine is undesirable, and the presence of such impurities in the crushed product renders the coal less valuable.

My invention is designed to provide a machine which will automatically discharge any such objectionable material, and to that end resides in a machine embodying the features hereinafter described, shown in the accompanying drawing, and then pointed out in the claims.

In the accompanying drawing:—Figure 1 is a longitudinal section. Fig. 2, an end elevation, omitting the screen shown in Fig. 1.

In said drawing the reference numeral 1 designates the cylinder in which the revolving hammers 2 work. 3 designates the cage or grinding-surface that co-operates with said hammers and which is preferably pivoted at 4, all as is well known in the art.

40 In rear of the grinding surface or cage 3, as viewed in respect of the direction of rotation of the hammers 2, the cylinder 1 is provided with a transverse passage 7 through which relatively hard or less friable material passes under the influence of centrifugal force. A fender 6, preferably inclined as shown, is provided at one edge of the transverse passage 7 and stands in the path of movement of the material in the cylinder. 45 This fender 6, as shown, is supported by a part 5 of the frame-work of the machine, and as hereinafter described may be adjustably connected to said part so that a passage of predetermined area may be maintained 50 and at the same time adjustment of the cage

3 to compensate for the wear of the hammers 2 permitted.

The passage 7, in the illustrated embodiment of the invention, is provided by a space between the end of the cage and the fender, 60 and leads to a slide 8, on which such material passes away. In order that any crushed or pulverized material that may be deflected through the passage 7 together with the eliminated foreign matter may be saved and 65 delivered into the pit 9 with the mass of crushed matter passing through the usual openings through the cage, the slide 8 is preferably a screen movably supported on a bracket 10 carried by the machine-frame, on 70 which it may be reciprocated in any suitable way, as by means of an eccentric pitman 11, as shown.

12 designates a deflector arranged to guide the crushed or pulverized material 75 that passes through the screen 8 to the pit 9 beneath the cage 3.

The fender 6 may be adjustably supported as by means of a slot and bolt connection 13, and the area of the passage 7 may be 80 made adjustable by means of a gage 14, shown as a screw stud adjustably fitted in the cross-bar 15 connecting the free ends of the cage-carrying arms 16, and adapted to abut against a bracket 17 connected to the 85 adjustable fender 6. The meeting of the gage and the bracket determines the limit of movement of the cage toward the fender, and it is obvious that by manipulating the gage the area of passage 7 may be varied. The 90 described adjustability of the fender may be availed of to permit the cage to be adjusted to and from the hammers to compensate for wear of the latter and still maintain the free passage 7 for the discharge of uncrushable matter as set forth. 95

When impurities, such as slate and sulfur balls, accompany coal to be crushed, and which are less friable or harder than the coal and therefore are not apt to be crushed the 100 first time they pass over the grinding surface, such impurities are, as described, discharged through the passage 7 instead of being carried about in the cylinder and possibly by repeated action of the hammers 105 broken up sufficiently fine to pass through the openings of the grinding surface with the crushed coal, which is undesirable and lessens the value of the coal. The machine, therefore, causes a separation between the 110

material to be crushed and impurities accompanying the same based on the relative friability of such material.

While the utility of the machine has been set forth with respect to crushing coal, the invention is not intended to be limited to such use, but is claimed for all the uses of which it is capable, as it provides a very simple and efficient means for automatically discharging from the machine objectionable hard or less friable material that may enter the machine with the material to be crushed.

The cage 3 in practice is ordinarily secured to the cage frame 16 by bolts, and after much use may have to be renewed. To enable the worn cage to be removed and a new one substituted it is desirable to provide that the cage may be lowered sufficiently to enable access to be easily had for the removal of the old and the substitution of the new cage. Although the same is not concerned in the present invention, means are provided by which the cage may be easily lowered and raised again and whereby also the cage may be adjusted with nicety to compensate for the wear of the hammers. This means consists of chains 18 passing over pocket sheaves 19 carried by a shaft 20, which shaft may be rotated to take up or let out the chains, by any suitable means, (which are not shown as the invention is not concerned therewith). Weights 21 are also connected to the cage to assist its downward movement when the chains are paid out by the pocket sheaves 19.

Having thus described the invention, what I claim is,—

1. A crushing machine comprising a cylinder, a portion of which constitutes a grinding surface or cage having openings for the passage of crushed material, said cylinder having a transverse passage opening therefrom in rear of the grinding surface or cage, a wall of said passage being adjustable relatively to said cage whereby a passage of predetermined area may be maintained and the cage adjusted to compensate for wear of the hammers.

2. In a crushing machine, the combination with a cylinder comprising a grinding surface or cage having openings for the passage of crushed material, and revolving hammers arranged in said cylinder, of a fender extending transversely of the crushing cylinder in the path of material in said cylinder, said cylinder having a passage communicating with said fender.

3. In a crushing-machine, the combination with a cylinder comprising a grinding-surface or cage and revolving hammers arranged in said cylinder, of a fender extending transversely of the crushing-cylinder in the path of material in said cylinder, said cylinder having a passage communicating with said fender, and means for adjusting the size of said passage.

4. In a crushing machine, the combination with a cylinder comprising a grinding surface or cage having openings for the passage of crushed material, and revolving hammers arranged in said cylinder, of a fender extending transversely of the crushing cylinder in the path of material in said cylinder, a slide located outside the crushing cylinder, and a passage leading from the fender to said slide.

5. In a crushing machine, the combination with a cylinder comprising a grinding surface or cage, having openings for the passage of crushed material, and hammers arranged in said cylinder, of a fender extending transversely of the crushing cylinder in the path of material in said cylinder, a screen located outside the crushing cylinder, said cylinder having a passage leading from the fender to said screen.

6. In a crushing-machine, the combination with a cylinder comprising a pivoted grinding-surface or cage, revolving hammers arranged in said cylinder, of a fender extending transversely of the crushing cylinder in the path of material in said cylinder, a bracket carried by said fender, and an adjustable gage carried by said cage or grinding-surface to coöperate with said bracket.

7. In a crushing machine, the combination of a cylinder comprising a grinding surface or cage having openings for the passage of crushed material, and hammers arranged in said cylinder, said cylinder having a transverse passage opening therefrom in rear of the grinding surface or cage, a screen located outside the crushing cylinder adjacent said transverse passage, and a deflector combined with said screen to lead material passing therethrough toward the space beneath the grinding surface or cage.

In testimony whereof I have hereunto set my hand in presence of two subscribing witnesses.

JOSEPH L. HILLER.
